UNITED STATES PATENT OFFICE.

ARTHUR J. BAZELEY, OF CLEVELAND, OHIO, ASSIGNOR, BY MESNE ASSIGNMENTS, TO NATIONAL MALLEABLE AND STEEL CASTINGS COMPANY, OF CLEVELAND, OHIO, A CORPORATION OF OHIO.

UNCOUPLING MECHANISM FOR CAR COUPLERS

Application filed February 12, 1921. Serial No. 444,339.

To all whom it may concern:

Be it known that I, ARTHUR J. BAZELEY, a citizen of the United States; residing at Cleveland, Cuyahoga County, Ohio, have 5 invented new and useful Improvements in Uncoupling Mechanisms for Car Couplers, of which the following is a specification, reference being had to the accompanying drawings, in which—

10 Fig. 1 is a plan showing the application of my improved uncoupling mechanism to a coupler and the under-framing of a car; Fig. 2 is a front elevation of the uncoupling mechanism showing the manner in which it 15 is suspended from a car; Fig. 3 is a side elevation thereof with the uncoupling mechanism in normal depending position and coupler in locked position; and Fig. 4 shows the position of the uncoupling mechanism 20 upon actuation and with the coupler in knuckle thrown position.

My invention relates to uncoupling mechanism of the bottom operated type, particularly designed for use with couplers 25 equipped with centering mechanisms by which the coupler is automatically returned to the longitudinal center line of the car. Suitable types of centering mechanisms are shown in my co-pending application Serial 30 No. 372,421, filed April 9, 1920. My invention comprises means for actuating the coupler operating mechanism regardless of the extent to which the coupler is angled laterally, and consists in the construction and 35 arrangement of parts which I shall herein-after describe and claim.

Referring to the drawings, 2 indicates a car coupler which is pivoted at 3 for movement transversely of the car. Attached to 40 the under side of the coupler is a lock lifter 4 of the bottom operated type. Secured in the eye 5 of the lifter 4 is a lifting rod 6 by which lifter 4 is actuated. The rod 6 extends rearwardly through, and is loosely 45 supported by, a hanger 7, so that it is free to move in all directions with the coupler. The hanger 7 depends from the brackets 8, which support the coupler centering mechanism 9.

50 Beneath the rod 6 is another rod 10, preferably of bail-like shape, loosely suspended in the links 11, which depend from the brackets 8. The ends 12 of the bail 10 are bent substantially at right angles to the

plane of the middle portion of the bail 55 and each end 12 is engaged by the inner end of an actuating member 13, which loops around the bail 10 adjacent an end 12 in such manner that the rotation of either of them rotates the bail 10.

60 Actuation of either member 13 by its handle 14 causes the bail 10 to rotate and to be elevated into contact with the lifter rod 6 between its connection with the lock lifter 4 and its fulcrum in the hanger 7. 65 As the rotation is continued the bail 10 lifts the rod 6, and as the rod 6 fulcrums against the hanger 7 the forward end of the rod is forced upwardly, carrying with it the lock lifter 4, thus operating the coupler. It will 70 be seen that where one of the members 13 is actuated the corresponding member 13 at the opposite side of the car is not disturbed, and that as soon as the pressure on a member 13 is relieved the member 13 and bail 10 75 are free to drop back to normal position, leaving the coupler either in lock-set or knuckle-thrown position.

I have found that the construction which I have described is of particular advantage, 80 since the bail will operate the lifter rod no matter what position the coupler assumes relative to the center line of the car, for the reason that the bail is curved forwardly on a radius so that the distance between 85 the point of attachment of the rod 6 to the lock lifter 4 and the point at which it engages the rod 6 is always substantially the same, regardless of the extent to which the 90 coupler has angled laterally, thereby eliminating the possibility of a loss of efficiency in the force applied to the actuating member through friction between the lifting rod and the bail.

95 As the bail 10 rotates upwardly in lifting the rod 6, its point of contact with the rod does not move along the rod because of the fact that the bail 10 is journaled in links 11 which are free to swing as shown in Fig. 4, which eliminates a sliding engagement and friction between the bail and rod.

100 The terms and expressions which I have employed are used as terms of description and not of limitation, and I have no intention, in the use of such terms and expressions, of excluding any mechanical equivalents of the features shown and described,

or portions thereof, but recognize that various structural modifications are possible within the scope of the invention claimed.

What I claim is:

- 5 1. An uncoupling mechanism for a coupler mounted for radial movement in a car, comprising a lifting rod carried loosely in a bracket and engaging the lock operating mechanism of said coupler, a bail-shaped 10 member extending laterally beneath said lifting rod, floating supports depending from the underframing of the car for suspending the bail intermediate its ends, the bail being so mounted on its floating supports that upon actuation it will engage the 15 rod at substantially the same distance from the point of engagement of the rod to the lock operating mechanism during the uncoupling operation, and a plurality of laterally extending operating rod members, 20 each of the said operating rod members having an end connected to an end of the bail, each member at each such connection having its end arranged at an angle to its body and 25 one of the said ends terminating in a loop taking about the body of the other of said members whereby one of said rod members is flexibly connected to the bail for limited rotation with said bail in one direction but 30 independently of the said bail in the other

direction, the said connection between the bail and the other rod member being inoperative except upon actuation by its operating handle.

- 35 2. An uncoupling mechanism for a coupler mounted for radial movement in a car, comprising a lifting rod member carried loosely in a bracket and engaging the lock operating mechanism of said coupler, a bail-shaped member extending laterally beneath 40 said lifting rod, floating supports depending from the underframing of the car for supporting the bail intermediate its ends, the bail being so mounted on its floating supports that upon actuation it will engage the 45 rod at substantially the same distance from the point of engagement of the rod to the lock operating mechanism during the uncoupling operation, a laterally extending operating rod member having an end connected 50 to an end of the bail, each member at such connection having its end arranged at an angle to its body and one of said ends terminating in a loop taking about the body of the other of the said members, whereby the 55 said operating rod member is flexibly connected to the bail for limited rotation with said bail in one direction but independently of the said bail in the other direction.

ARTHUR J. BAZELEY.
